(57) **CLAIM**

The ornamental design for a fence panel, as shown and described.

DESCRIPTION

FIG. 1 is a perspective view of a fence panel;

FIG. 2 is a front elevational view of the fence panel shown in FIG. 1;

FIG. 3 is a rear elevational view of the fence panel shown in FIG. 1;

FIG. 4 is a left side view of the fence panel shown in FIG. 1;

FIG. 5 is a right side view of the fence panel shown in FIG. 1;

FIG. 6 is a top view thereof; and,

FIG. 7 is a bottom view thereof.

The drawings contain a symbolic break. The portion between the break lines form no part of the claimed design.
